UNITED STATES PATENT OFFICE.

LEON M. HARWOOD, OF SPRINGFIELD, MASSACHUSETTS.

DEVICE FOR APPLYING METALLIC LEAF.

1,373,424.

Specification of Letters Patent.

Patented Apr. 5, 1921.

Application filed November 29, 1920. Serial No. 427,078.

To all whom it may concern:

Be it known that I, LEON M. HARWOOD, a citizen of the United States, residing at Springfield, in the county of Hampden and 5 State of Massachusetts, have invented new and useful Improvements in Devices for Applying Metallic Leaf, of which the following is a specification.

This invention relates to improvements 10 in devices for applying metallic leaf.

An object of the invention is to provide a conveniently operable device for drawing the metallic leaf, and its supporting strip, from the wound package roll in such a 15 manner that the roll may be unwound without liability of the leaf adhering to the outside of the supporting strip and thereby following around the roll instead of unwinding as desired.

20 Another object of the invention is to provide a roll for the purpose of receiving and depositing the metallic leaf, which roll has a portion only of its peripheral surface of material capable of being electrified, where- 25 by the leaf may be attracted near its leading end to the roll and held until it is deposited thereby.

A further object of the invention is to 30 provide a movable carriage, having a receiving and depositing roll and supporting means for a package roll of metallic leaf, together with directing means to guide the supporting strip away from the leaf as it is deposited upon the work and to guide 35 such strip in such a manner that a pull thereon, after it leaves the directing means, will unwind the leaf from the roll and advance the carriage along the work.

Other objects and advantages will appear in the following description and in the 40 illustrative embodiment of the invention in the accompanying drawings, in which,—

Figure 1 is a plan view of a device embodying the invention;

45 Fig. 2 is a side elevational view thereof; and

Figs. 3 and 4 are plan views of two forms of receiving and depositing rolls for use in the device.

50 Referring to these drawings: the device in its broadest aspects involves suitable supporting means for a package roll of metallic leaf and a bed adjacent thereto, which is so constructed as to be capable of attracting 55 the leaf as it, together with its supporting

strip, is unwound from the package roll and thereby preventing adherence of the leaf to the outer side of the supporting strip.

As shown, the supporting means consists of an arbor 5 upon which the package roll 60 *r*, (consisting of a supporting strip with leaf, previously deposited thereon, wound upon a hollow core into roll form) is slipped. Arbor 5 is suitably mounted at its ends in slots 6 in spaced frames 7 and in 65 such a manner as to be conveniently removable, being held in slots 6 by retainers 8, which may readily be loosened and swung upwardly to release the arbor.

Also mounted in frames 7 are rods 9 and 70 10, arranged one on each side of arbor 5 and in parallelism therewith. These rods support between them one or more bands 11, which constitute the electrifying bed 75 above referred to. The bands 11 may be and preferably are of rubber, which is flexible, elastic and capable of being electrified, although other suitable material may be provided if desired. Adjustably mounted in each frame 7, as by the screw threads 80 shown, is a downwardly extending member 12 and extending between the two members 12 and bearing against the bands 11 is a cross-bar 13. By turning the members 12, cross-bar 13 may be moved up and 85 down to bring the bands 11 toward or away from the package roll *r* on arbor 5, thus providing for adjustment of the bed according to the size of the package roll or 90 for other purposes as desired.

In connection with the device described, there is preferably employed a receiving roll; or more properly a receiving and depositing roll. Such a roll is shown at 14 and is journaled at its ends in the forward 95 part of frames 7. The supporting strip *s* with metallic leaf *l* is led from the package roll *r* to roll 14 over the intervening bed 11 and, in drawing the strip over the bed, frictionally electricity is generated to attract the leaf *l* and prevent it from following around roll *r* by adherence to the outer side of strip *s*. The roll 14 is moved over the work, as *w*, and deposits the leaf thereon.

To assist in the operation described, the 100 frames 7 preferably constitute part of a movable carriage which includes rearwardly extending bars 15 secured to frames 7 and suitable means, such as wheels 16 upon rod 10, to support the carriage for movement, 110

with the roll 14 bearing upon the work *w*. Also, directing means, such as a roll 17, is employed which guides strip *s* away from the work *w* as leaf *l* is deposited and also 5 so directs the leading end of the strip that, as such end is pulled, an unwinding of roll *r* ensues as well as a simultaneous advancing movement of the carriage. Preferably, one or more rolls 18 coöperate with roll 17 10 to frictionally hold the strip *s* to roll 17 and permit tensioning of strip *s*.

The receiving roll 14 may be variously constructed as desired, as with a peripheral covering of suitable material, such as rubber 15 or the like, which is capable of being frictionally electrified. The roll may be entirely covered with rubber, or the like, or only partially so, as by one or more relatively narrow peripheral bands 19 (Fig 4), 20 or by one or more relatively narrow longitudinal bands 20 (Fig. 3). The amount of peripheral surface of roll 14, having electrifiable material, may therefore be varied as desired according to the degree of attraction 25 which is necessary or desired to hold the leaf to the roll. Preferably also, a brush 21, having a surface, such as of wool or the like, to engage roll 14, is provided to increase the electric attraction for the leaf 30 by frictioning the rubber as roll 14 turns.

A desirable arrangement is shown in Fig. 3, for the single longitudinal strip 20 may be arranged to attract merely a part of the leaf, as near its leading end, and, being 35 held in such a manner, the leaf will follow around the roll 14 and be deposited, correctly positioned, upon the work. A knob or handle 22 may be removably secured to roll 14, as indicated in Fig. 1, so that, after 40 strip *s* has been drawn out sufficiently to bring the leading end of the leaf *l* over roll 14, the latter may be manually turned (while lifted out of contact with work *w*) to bring the electrified part 20 into position to attract 45 the leading end of the leaf.

In operation, the package roll *r* having been placed on arbor 5, the strip *s* is drawn out and around roll 14 and is threaded between rolls 17 and 18. The carriage, being 50 suitably supported, in the manner illustrated or otherwise, the receiving roll 14 is positioned as desired upon work *w*. The strip *s* is then pulled which results in moving the carriage along the work and the unwinding of roll *r*. As the strip *s* passes over the electrifiable bed 11, the leaf is attracted thereby and prevented from following 55 around roll *r*, thus insuring that the leaf travels forwardly properly held to strip *s*. 60 As the roll *r* diminishes in diameter, the bed 11 is adjusted from time to time by the members 12 to compensate for the change in size. Adjustment of members 12 may also be made to control the degree of proximity of 65 bed 11 to the package roll and the degree of

contact of bed 11 with strip *s*. Whenever desired, the roll 14 may be lifted from work *w* and strip *s* pulled out without moving the carriage to bring leaf sections into proper relation with roll *r*, to be later deposited in 70 the desired position on the work *w*.

Many changes in detail and variations in structure may be made in the one exemplary form of the device heretofore described without departing from the scope of the invention and I do not desire to limit myself to various elements of the structure disclosed except as such elements appear in the following claims.

What I claim is—

1. In combination, supporting means for a package roll of metallic leaf, and a bed over which the leaf with its supporting strip may be drawn as it is unwound from the roll and electrified to prevent its adhesion 85 to the outer side of the supporting strip.

2. In a device for applying metallic leaf, supporting means for a package roll of metallic leaf, a receiving roll, and an intervening bed of suitable material capable of 90 attracting the leaf by frictional electricity, whereby when the leaf is unwound from the package roll it is prevented from adhering to the outer side of the supporting strip.

3. In a device for applying metallic leaf, supporting means for a package roll of metallic leaf, a receiving roll, an intervening bed of suitable material capable of attracting the leaf by frictional electricity, whereby when the leaf is unwound from the package roll it is prevented from adhering to the outer side of the supporting strip, and means for moving said bed and supporting means, the one relatively to the other.

4. In a device for applying metallic leaf, a receiving roll for the leaf having a surface partially capable of being electrified to hold the leaf by electric attraction in position on the roll.

5. In a device for applying metallic leaf, a movable carriage, supporting means for a package roll of metallic leaf mounted in said carriage, a receiving roll in the latter over which the leaf with its supporting strip is 115 drawn and by which the leaf is deposited upon the work, and guiding means to lead the supporting strip from the receiving roll away from the deposited leaf and to direct the leading end of the strip so that a pull thereon will unwind the leaf and strip from the package roll and will advance the carriage along the work.

6. In a device for applying metallic leaf, a movable carriage, supporting means for a package roll of metallic leaf mounted in said carriage, a receiving roll in the latter over which the leaf with its supporting strip is drawn and by which the leaf is deposited upon the work, a bed between said support- 120

ing means and receiving roll to electrify the leaf as it passes thereover to prevent the leaf adhering to the outer side of the supporting strip, and guiding means to lead the supporting strip from the receiving roll away from the deposited leaf and to direct the leading end of the strip so that a pull there-

on will unwind the leaf and strip from the package roll and will advance the carriage along the work.

10

In testimony whereof I have affixed my signature.

LEON M. HARWOOD.
